UNITED STATES PATENT OFFICE

91,210

DESIGN FOR A CABINET

Henry I. Morin, Springvale, Maine, assignor to Springvale Wood Working Co. Inc., Spring-vale, Maine, a corporation of Maine

Application October 9, 1933. Serial No. 49,428

Term of patent 7 years

To all whom it may concern:

Be it known that I, HENRY I. MORIN, a citizen of the United States of America, residing at Springvale, town of Sanford, county of York, and State of Maine, have invented a new, original,
and ornamental Design for a Cabinet, of which the following is a specification, reference being had to the accompanying drawing, forming part thereof.

Figure 1 is a perspective view of a cabinet showing my new design; and Figure 2 is a top plan view of the same.

I claim:

The ornamental design for a cabinet, as shown.

HENRY I. MORIN.
